UNITED STATES PATENT OFFICE.

ELWOOD M. COLE, OF LEWISTON, MAINE.

WEFT STOP-MOTION FOR LOOMS.

SPECIFICATION forming part of Letters Patent No. 251,699, dated January 3, 1882.
Application filed July 28, 1881. (No model.)

To all whom it may concern:

Be it known that I, ELWOOD M. COLE, of Lewiston, of the county of Androscoggia and State of Maine, have invented a new and useful Improvement in Weft Stop-Motions for Looms; and I do hereby declare the same to be described in the following specification and represented in the accompanying drawings, of which—

10 Figure 1 is a top view, and Fig. 2 a transverse section, of the lay and breast-beam of a loom with my stop-motion applied thereto. Fig. 3 is a side view, and Fig. 4 a bottom view, of the catch-lever N, hereinafter mentioned.

15 Fig. 5 is a top view of the bracket L. The nature of my improvement is defined in the claim hereinafter made.

In such drawings, A denotes the race-beam of the lay, and B the breast-beam of a loom-frame.

Extending transversely across, or nearly across, the top of the lay is a channel or groove, a, to receive the prongs b of a fork, C, pivoted within a support-piece, D, that is fastened to 25 the inner face of the lay, the same being so as to admit of the fork being turned up or down in a vertical plane. Fixed on one of the journals c of the said fork is a sectoral gear, E, from which an arm, F, in one piece with such 30 gear, projects toward the lay, in manner as shown, and is provided near its free end with a stud, d, such stud being extended into the slot e of a connecting-rod, G, that depends from the said stud. At its lower part the rod is 35 jointed to a tripping-pawl, H, arranged with and pivoted to a bracket, g, affixed to the race-beam, as shown. Furthermore, the toothed sector or sectoral gear E engages with another such gear, f, which constitutes the upper and 40 shorter arm of a lever, I, formed and arranged as shown, and fulcrumed in or to the support-piece D. Fixed to the said piece D, and to extend over and cover the sectoral gears, is a 45 guard or shield, K, which is to prevent an attendant of the loom from accidentally interfering with the gears. The said guard also protects such gears from becoming choked by waste or by a broken filling or weft yarn.

Attached to and projecting from the breast-beam and toward the lay is a bracket, L, whose horizontal portion is channeled rectilinearly

to receive a furcated slider, M, between whose prongs, and fulcrumed thereto, is a catch-lever, N, formed as represented in side view in Fig. 3 and in under side view in Fig. 4. The bracket 55 L has, besides the groove or channel, slots m n arranged in it, as shown. The slider M extends through the bracket, and is jointed to an arm of a right-angular-lever-shaped spring, O, fulcrumed to the breast-beam, and arranged 60 as shown. The other arm of the lever O rests against a projection, o, from the slide-rod p, usually applied to the shipper of the loom. By moving the said slide-rod by the lever-spring O the shipper of the loom will be forced out of 65 its catch-notch, in which case the driving-belt, by the elastic power or spring of the shipper, will be moved from its driving to its loose pulley, so as to produce stoppage of the loom, as well understood by persons skilled in the 70 making and using of looms.

In Fig. 2 the positions the main parts of the stop-motion assume when the lay is at the greatest distance from the breast-beam are represented by dotted lines.

The operation of the said stop-motion may be thus described: While the weaving of a piece of cloth is progressing and the filling-thread carried by the shuttle through the shed of the warps and across the race-beam is unbroken, the prongs of the fork cannot fall into the groove a, as they will rest upon the filling; but should such thread become broken and not extend across the said groove the prongs will fall into the groove. In so falling into the 85 groove the fork, by means of the sectoral gears, will depress the connecting-rod G so as to allow the pawl H, by its gravitating power, to fall sufficiently for it, in the next movement of the lay toward the breast-beam, to be carried 90 against the shoulder q of the catch-lever N, and thereby cause a rearward movement of the slider M, and consequently such a movement of the lever-spring O as will insure a stoppage 95 of the loom. While the slider M is being so moved the catch-lever N, moving with it, will be drawn out of the rear slot, m, and depressed into the front slot, n, whereby the shoulder q will be moved out of engagement with the pawl. While the shipper is being restored to 100 its notch the slide-bar will be so moved by the shipper as to cause the lever-spring O to crowd

the slider M backward within the bracket, and thereby cause the longer arm of the catch-lever N to pass into the notch *m* sufficiently to raise the shoulder *q* to its position to be met by the 5 pawl when next properly lowered therefor. The lay, in going back, carries the lower inclined end, *r*, of the lever I against a projection, *s*, so as to cause the fork C to be tilted high enough for the shuttle, at its next throw, to pass 10 under and without contact with the prongs of the fork. Immediately on the lay commencing to break up, the lever I will be moved away from the projection *s*, so as to enable the fork to drop upon the filling extending across the 15 groove *a*.

The slot *e* of the connecting-rod G is to allow the pawl, during the back movement of the lay, to rise and pass over the catch N without at the same time creating any movement 20 of the fork, whose prongs at such end are within the groove *a*.

The prongs *b* of the fork C are in one piece, bent at its middle, like a hair-pin, the same being as shown in Fig. 6. They go through

the shank *t* of the fork at right angles thereto, 25 and are held therein by clamp-piece *u*, forced against them at their junction by a screw, *v*, going through the said clamp-piece and screwed into the shank. On loosening the screw and turning the clamp-piece down upon it the 30 prongs of the fork, when injured, can be extracted from the shank and others readily substituted.

Fig. 7 is a vertical section of the fork-shank, the clamp-piece, and its fastening-screw. 35

What I claim as my invention is—

The combination substantially as described, such consisting of the lever-spring O and the stop-motion fork C, lever I, arm F, sectoral gears E and f, slotted connection-rod G, pawl H, projection *s*, slotted and grooved bracket L, slider M, and catch-lever N, all arranged and adapted to operate essentially as set forth. 40
